UNITED STATES PATENT OFFICE.

WILLIAM H. AYER, OF CLAREMONT, NEW HAMPSHIRE.

SHUTTLE-CHECK FOR LOOMS.

No. 872,779.

Specification of Letters Patent.

Patented Dec. 3, 1907.

Application filed March 7, 1906. Serial No. 304,737.

To all whom it may concern:

Be it known that I, WILLIAM H. AYER, a citizen of the United States of America, residing at Claremont, in the county of Sullivan and State of New Hampshire, have invented new and useful Improvements in Shuttle Checks for Looms, of which the following is a specification.

This invention relates to shuttle checks for looms, and particularly for looms of that class wherein the shuttle checking is carried out by the action of the check on the picker stick. The invention is applicable in this connection to looms in which the picker 10 is connected with the picker stick or in which the picker runs on a picker rod.

The object of the invention is to provide a check of simple construction which will effectually cushion the impact of the shuttle 20 on the picker and hold the picker stick, and consequently the picker and shuttle, from rebounding or moving forward, thereby obviating the necessity of using heavy friction on the shuttle binder and preventing 25 the loss of shuttle throwing power which occurs when the shuttle is permitted to have a forward or rebounding movement.

Another object is to provide a check which will hold the picker stick directly in line with 30 the shuttle point and which is applicable to the lays of different types of looms and is adjustable to properly position it for action thereon.

In the accompanying drawings, —Figure 1 35 is a view in side elevation of one end of a lay having my improved shuttle check applied thereto and showing the picker stick in dotted lines. Fig. 2 is a bottom plan view of the same, omitting the picker stick. Fig. 3 is a 40 perspective view of one form of check. Fig. 4 is a detail view of the bracket or hanger. Fig. 5 is a horizontal section through a modified form of bracket.

Referring now more particularly to the 45 drawings, the numeral 1 denotes one of the end portions of a lay, the same being provided with the slotted guideway or race 2, in which the upper end of the picker stick 3 fits and plays.

50 The check 4 is formed of spring metal and comprises a narrow vertical body plate or portion 5 provided with forwardly extending wings or cheek plates 6. These wings or cheek plates extend a short distance in parallel relation from the body portion 5 and are thence outwardly curved or flared, as

indicated at 7, to form a mouth or entrance space to the check which gradually decreases in width toward the parallel portions.

In the form of the invention shown in Fig. 60 3, the check 4 is composed of a single piece of spring metal bent into the described form, whereas in Fig. 2 the check is illustrated as being composed of two parts or inner and outer members 4^a and 4^b having the construction set forth, one of said members being fitted within the other. If desired, however, the check may be constructed of a single piece of metal having wings or cheek pieces of double length, with their outer 65 halves folded inwardly to give a double ply formation and to correspondingly stiffen and strengthen the wings or cheek pieces. In either construction a ply or layer of leather 8, which may simply cover the inner faces of 70 the wings, or correspond in contour to and extend around the inner surface of the check, may be used in order to secure the desired frictional pressure against the picker stick and prevent undue wear thereon and on the 75 wings of the check. The check is supported below the end of the lay by suitable supporting means, that shown in the present instance comprising a bracket or hanger 9 consisting of a metallic strap bent or folded centrally upon itself to provide parallel arms 10 and 11 connected at their upper ends by a head or union piece 12, both arms being formed with series of alining perforations 13. The bracket or hanger as thus constructed 80 forms a saddle or stirrup which is hung upon the outer end of the lay 1 with its head or union piece 12 resting upon the narrow wall between the end of the lay and the outer end of the race 2, and the arms 10 and 11 respectively projecting downwardly through the race and against the outer end surface of the lay and projecting some distance below the same. The arms of the bracket are connected to each other by bolts 14 passing 85 through the alining perforations 13 and carrying clamping nuts 15, two or more of the upper bolts of the series also extending through the outer end of the lay and the body portions and securing the bracket thereto, 90 while the depending ends of the arms of the bracket bear against the inner and outer surfaces of the body portion or portions of the check and clamp the same to the bracket. The leather layer 8 may be fastened in any 95 preferred manner to the check, but as shown in the present instance is fastened at its ends 100 105 110

to the ends of the wings by rivets 16 passing through perforations 17 formed in said wings, the rivets also, in the construction shown in Fig. 2, passing through the plies of 5 the two-part check and holding the same rigidly connected.

It will be observed that the check is free when the bolts below the lay are loosened to be adjusted vertically relative to the lay to 10 arrange it closer to or further from the same to suit different conditions of service, and that by tightening the bolts it will be firmly and securely clamped in adjusted position.

In the operation of the device the picker 15 stick 3 in its outward movement under the impact of the shuttle on the picker passes between the divergent ends of the cheek pieces or wings 6 and comes in contact with the leather ply 8 which exerts frictional pressure 20 thereon to retard its movement until when the stick enters the space between the parallel portions of the cheek plates, its motion will be entirely arrested. By this means the picker stick will be brought gradually to a 25 stop without shock or jar, and the impact of the shuttle properly cushioned. When the stick contacts with the check at the point where the wings begin to flare outwardly, the latter will spread apart to a slight extent under 30 the pressure of the stick and then, upon the passage of the stick into the space between the parallel portions of the wings, will, by their spring action, bear against the stick and exert sufficient frictional pressure there- 35 on to prevent the stick from rebounding or moving forward. By this means the impact of the shuttle on the picker will be effectually cushioned and the parts prevented from having the usual rebound or forward move- 40 ment, thereby obviating the necessity of using heavy friction on the shuttle binder and preventing the loss of shuttle throwing power which occurs when the shuttle is permitted to have such rebounding movement. 45 The picker stick will be held in the check until it is positively actuated in the reverse direction by the loom mechanism, as will be readily understood.

Projecting downward from the lay on opposite 50 sides of the race 2 are pins 18 which bear against the inner faces of the outer ends of the wings or cheek pieces 6 and hold the same spread the desired distance apart and limit their inward movement, so that they 55 will not bear with undue pressure upon the picker stick. The wings slide in contact with these pins so that the check may be adjusted vertically without interference therefrom.

60 The construction of hanger or means for supporting the check from the lay may be varied to suit variations in the construction of the lays of different machines of the type referred to. For instance, in some makes of 65 machines, the inner arm of the hanger

bracket cannot be extended downward through the lay. The construction in such cases may be varied by simply cutting away the upper part of the arm 10 from the head 12 downward a distance equivalent to the 70 vertical thickness of the end of the lay, leaving the lower portion of said arm 10 free to act as an independent clamping jaw to clamp the check against the arm 11 below the lay, as will be readily understood. Other changes, 75 such as clearly fall within the spirit and scope of the invention, may also be made to suit different conditions of service, without departing from the spirit of the invention or sacrificing any of the advantages thereof. 80

In the construction shown in Fig. 5 the inner or forward arm 10' of the bracket is of less width where it is engaged by the body portion of the check than the outer or rear arm 11', and the rear surface of said arm 10' 85 is convexed or rounded, while the body portion 5' is correspondingly shaped to bear against the same and extends laterally therebeyond. This form of the body portion 5' allows the wings of the check to have a 90 greater range of outward movement. Set screws 19 are arranged on the arm 11' to impinge against the rear surface of the body portion on opposite sides of the center thereof, whereby the extent of spreading move- 95 ment of the wings may be regulated, and check nuts 20 are provided upon the screws to lock them in adjusted position. This construction secures a wider range of cushioning movement of the wings. 100

Having thus described the invention, what is claimed as new, is:—

1. A shuttle check for looms, comprising a body having spring wings or cheek pieces, arranged to form a receiving space and a widened entrance thereto, a bracket on which the check is vertically adjustable, and means for clamping the body portion of the check to the bracket. 105

2. In a shuttle check for looms, the combination with a lay, of a hanger attached thereto and hanging pendent therefrom, and a check supported by said hanger below the end of the lay, said check being vertically adjustable on said hanger and provided with 115 divergent wings forming a space to receive the picker stick and adapted to exert a gradual frictional pressure thereon to bring said stick to a stop.

3. In a shuttle check for looms, the combination with a lay, of a hanger mounted upon the outer end of the lay and depending therefrom, a check supported by the hanger below the end of the lay, said check having spring actuated wings or cheek pieces provided with 120 outwardly curved or flared ends, and stop pins projecting downward from the lay to limit the inward movement of said wings or cheek pieces. 125

4. In a shuttle check for looms, the combi- 130

nation with a lay, of a supporting device secured to the end of the lay and hanging pendent therefrom, a check disposed below the end of the lay and carried by said supporting device, said check being adjustably connected with said supporting device for vertical movement toward and from the lay and having spring cheek pieces formed with diverging ends, and stop pins projecting downward from the lay and engaging said diverging ends of the cheek pieces to limit their inward movement, the cheek pieces being adapted to slide on the pins to permit the check to be adjusted without interference therefrom.

5. In a shuttle check for looms, the combination with a lay, of a supporting bracket attached thereto and hanging pendent therefrom, a check disposed below the end of the lay and having a body portion adjustably clamped between the arms of the bracket, spring means or cheek pieces projecting forwardly therefrom and having diverging ends, and stop pins projecting from the lay and bearing against said diverging ends to limit the inward movement of the cheek pieces.

20 6. In a shuttle check for looms, a bracket

provided with a suspending head and depending parallel arms, a shuttle check having its body portion disposed between said arms, and means connecting said arms for adjustably securing the shuttle check in position.

7. In a shuttle check for looms, the combination with a lay, of a bracket carried by and depending from the lay, a shuttle check carried by said bracket and provided with spring wings, and stops carried by the lay for controlling the action of said wings.

8. As an article of manufacture, a picker check for looms, comprising a shank, and a U-shaped picker-stick receiver fixed at its heel to the shank and having resilient arms curved slightly outward at their free ends and also having strips of leather arranged at 45 and fixedly connected to the inner sides of said arms.

In testimony whereof, I affix my signature in presence of two witnesses.
